UNITED STATES PATENT OFFICE.

LINCOLN SHACKELFORD, OF BONAPARTE, IOWA.

FURNACE.

Application filed October 17, 1921. Serial No. 508,211.

To all whom it may concern:

Be it known that I, LINCOLN SHACKELFORD, a citizen of the United States, residing at Bonaparte, in the county of Van Buren and State of Iowa, have invented a new and useful Furnace, of which the following is a specification.

This invention aims to provide a simple means whereby combustible elements carried in suspension by smoke or products of combustion, may be made available for heating a boiler, or for any other purpose.

It is within the province of the disclosure to improve generally and to enhance the utility of devices of that type to which the invention appertains.

I do not bind myself to the specific details depicted and described, since, within the scope of what is claimed, a mechanic may make changes in the form selected as one of the many possible material embodiments of the invention, without departing from the spirit of the invention or placing the utility thereof in jeopardy.

25 In the accompanying drawings:—Figure 1 shows in vertical longitudinal section, a device constructed in accordance with the invention; Figure 2 is a cross section on the line 2—2 of Figure 1; Figure 3 is a cross section on the line 3—3 of Figure 1; Figure 4 is a cross section taken horizontally and disclosing the burner construction.

In carrying out the invention there is provided a furnace including a bottom 1, sides 2, a front 3 and a back 4. A baffle 5 extends between the sides 2 and is located to the rear of the front 3, the baffle forming the back wall of a fire pot 6 including a grate 7, access being had to the fire pot by way of a stoke door 8 in the front 3, and access being had to the ash pit 10 through a clean-out door 9 carried by the front. To the rear of the baffle 5, a forward cross wall 11 extends between the sides 2. A rear wall 12 extends between the sides 2 and is disposed to the rear of the forward cross wall 11. The space defined by the walls 11 and 12 and the intervening portions of the sides 2 defines an intermediate chamber 32. A

50 platform 14 connects the rear cross wall 12 with the back 4, a lower chamber 15 existing below the platform, and an upper chamber 16 existing thereabove.

A first flue 17 is mounted at its ends in the cross walls 11 and 12 and extends through the intermediate chamber 32, the

flue establishing communication between the space 18 which exists between the baffle 5 and the wall 11 on the one hand, and the lower chamber 15 on the other hand. The 60 numeral 19 marks a second flue having its forward end mounted in cross wall 12, the rear end of the flue being disposed adjacent to the back 4. The flues 17 and 19 are disposed relatively near to the bottom 1. The 65 flue 17 is provided with a damper 20, controlled by any suitable operating means 21.

70 Burners are disposed in the intermediate chamber 32. Each burner embodies a bridge 22 having its ends mounted in the sides 2, the bridges being provided at their outer edges with longitudinal upstanding wings 23. The bridges 22 have longitudinal ribs 24 provided with inclined surfaces 25 overhanging the wings 23. Combustion 75 slits 26 exist between the bridges 22 and between the upstanding wings 23 thereof. Each rib 24 has a longitudinal passage 27 communicating with air inlet ports 28 in the sides 2. Each bridge has, further, 80 transverse apertures 29, communicating at their inner ends with the passage 27, and discharging at their outer ends on inclined surfaces 30 formed on the wings 23. The air inlets 28 are under the control of dampers 31 of any desired sort, the dampers being mounted to reciprocate, if desired, in guides 50 on the sides 2, and being provided with racks 33, coacting with pinions 34 on shafts 35 journaled in bearings 36 on the 85 sides 2.

A boiler 37 is mounted on the front 3 and the forward cross wall 11, there being a space 38 between the upper edge of the baffle 5 and the boiler, a space 39 existing 90 between the upper edge of the rear cross wall 12 and the boiler. An arch 40 may bridge the space between the rear end of the boiler 37 and the back 4. The outlet for the products of combustion traversing the boiler 100 is shown at 41.

In practical operation, the coal or other fuel is burned in the fire pot 6. The products of combustion pass rearwardly through the opening 38, downwardly through the space 105 existing between the baffle 5 and the wall 11, and longitudinally of the flue 17, under the control of the damper 20. Thence, the products of combustion enter the lower chamber 15 and circulate therein, the products 110 passing by way of the flue 19, into the intermediate chamber, below the burners.

Thence, the products pass upwardly through the slits 26. Air, under the control of the dampers 31, enters the inlets 28 in the walls 2 and passes into the passage 27 of the ribs 5 24 on the bridges 22, the air moving, longitudinally of the structure, through the apertures 29 and being directed upwardly by the inclined surfaces 30 of the wings 23, and by the wings 23, the air mingling with the 10 products of combustion traversing the slits 26, the mixture being directed inwardly the overhanging inclined surfaces 25 of the ribs, the mixture burning between the ribs, or closely adjacent thereto. The resulting products of combustion move rearwardly 15 through the opening 39, into the upper chamber 16, through the boiler and out of the outlet 41. The construction of the device is such that all combustible matter will 20 be burned, with a corresponding saving in fuel, and with the application of increased heat to the boiler.

What is claimed is:—

1. In a device of the class described, a 25 boiler setting comprising a front and a baffle forming part of a fire pot; a forward cross wall disposed to the rear of the baffle and spaced therefrom, the fire pot communicating with the space between the baffle and the cross wall, across the upper edge of the baffle; a rear cross wall spaced from the forward cross wall and defining an intermediate chamber therewith; a back, spaced from the rear cross wall; a platform extended 30 between the rear cross wall and the back and forming upper and lower chambers, the intermediate chamber communicating with the upper chamber across the upper edge of the rear cross wall; a flue extended through 35 the intermediate chamber and establishing communication between the space at the rear of the baffle and the lower chamber; means for conducting the products of combustion from the lower chamber into the intermediate chamber; burners in the intermediate chamber, above the flue; and a boiler supported on the front and on the forward cross wall and extended into the upper chamber, the burners being disposed beneath the 40 boiler.

2. In a device of the class described, a boiler setting having an intermediate chamber; bridges extended transversely of the intermediate chamber and provided with ribs having longitudinal air inlet passages 55 provided with transverse apertures; a fire pot on one side of the intermediate chamber; a lower chamber on the opposite side of the intermediate chamber; means for conducting the products of combustion from the fire pot through the intermediate chamber into the lower chamber; and means for conducting the products of combustion from the lower chamber into the intermediate chamber, beneath the bridges. 60

3. A device of the class described, embodying a fire pot; a lower chamber; an intermediate chamber between the fire pot and the lower chamber; a burner in the intermediate chamber; means for admitting air 70 to the burner; means for conducting the products of combustion from the fire pot through the intermediate chamber into the lower chamber; and means for conducting the products of combustion from the lower chamber into the intermediate chamber beneath the burner. 75

4. In a device of the class described, a fire pot, a lower chamber, and an intermediate chamber therebetween; bridges in the 80 intermediate chamber and having upstanding wings, the bridges having upstanding ribs located between the wings and provided with longitudinal air passages, the ribs having transverse apertures discharging between 85 the wings, the bridges being spaced to define slits between the wings; means for conducting the products of combustion from the fire pot through the intermediate chamber into the lower chamber; and means for conducting the products of combustion from the lower chamber into the intermediate chamber beneath the bridges. 90

In testimony that I claim the foregoing as my own, I have hereto affixed my signature 95 in the presence of two witnesses.

LINCOLN SHACKELFORD.
